DESIGN FOR OILCLOTH OR SIMILAR ARTICLE

Charles F. Scholle, Larchmont, N. Y., assignor to Standard Coated Products Corporation, New York, N. Y., a corporation of New York

Application December 27, 1938, Serial No. 81,999

Term of patent 7 years

To the Commissioner of Patents:

Be it known that I, Charles F. Scholle, a citizen of the United States, residing at Larchmont, in the county of Westchester and State of New York,
have invented a new, original, and ornamental Design for Oilcloth or Similar Article, of which the following is a specification, reference being had to the accompanying drawing, which forms
a part thereof.

The figure is a plan view of oilcloth embodying
my new design.

I claim:

The ornamental design for oilcloth or similar article, substantially as shown.

CHARLES F. SCHOLLE.
